DESIGN FOR A BOTTLE

Marcel Ott, Antibes, France

Application June 14, 1934, Serial No. 52,175

Term of patent 3½ years

To all whom it may concern:

Be it known that I, MARCEL OTT, a citizen of France, and residing in Antibes, Department of Alpes Maritimes, France, have invented a new, original, and ornamental Design for a Bottle, of which the following is a specification, reference being had to the accompanying drawing, forming part thereof;

The figure is a side elevational view of a bottle according to my design, the side opposite to that shown being substantially identical.

I claim:

The ornamental design for bottle as shown and described,

MARCEL OTT.
